United States Patent

Des. 237,976
Patented Dec. 9, 1975

237,976

KEYBOARD AND DISPLAY UNIT

William L. Wolfe, and Robert C. Zimmerman, Manlius,
and Gerald M. Adams, Fayetteville, N.Y., assignors to
SCM Corporation, New York, N.Y.

Filed July 29, 1974, Ser. No. 492,623

Term of patent 14 years

Int. Cl. D14—02

U.S. Cl. D26—5 C

FIG 1

FIG. 1 is a left front perspective view of a keyboard and display unit showing our new design;

FIG. 2 is a front elevational view thereof;

FIG. 3 is a top plan view thereof;

FIG. 4 is a right side elevational view thereof; and
FIG. 5 is a rear elevational view thereof.

We claim:

The ornamental design for a keyboard and display unit, as shown.
